CONTROL APPARATUS

Alexander W. Plensler, Chicago, Ill., assignor to
 Belmont Radio Corporation, a corporation of
 Illinois

Application May 8, 1941, Serial No. 392,475

17 Claims. (Cl. 74—10)

This invention relates in general to control apparatus and more in particular to a mechanical control device for a tuning system for radio receiving apparatus.

One form of the mechanical tuning devices of the prior art generally includes a rotatable treadle bar in operative connection with the tuning condensers, a linearly or pivotally movable station selector unit or push button being adapted to rotate the treadle bar to provide for a movement of the condensers to a particular predetermined tuning position corresponding to the station identified by the selector unit. In order that a few push button or selector units can be adapted to tune a large number of predetermined station frequencies, means are provided for making a relative adjustment or setting between the treadle bar and push button in some manner so that each unit may tune more than one station frequency, depending upon the particular setting. This adjustment or setting has been accomplished by some devices in the prior art by an adjustable element in each push button. In these devices, various means have been used to frictionally lock the adjustable element on the push button, but all of these means normally require the use of both hands of the operator during the setting operation so that adjustment is a clumsy and inconvenient operation and sometimes rather difficult.

Many of these prior devices require supplementary tools such as a screw driver or the like for changing the friction pressure on the adjustable element. Particularly in instances, such as in small portable receiver sets, where the selector units are spaced relatively close together, but little room is provided for both the positioning of the hands and manipulation of the screw driver. Apart from the inconveniences encountered in the adjustment operation, the accuracy of the adjustment is impaired by the tendency of the selector unit to move out of its home position while the screw driver is being used so that the adjusted position of the adjustable element is changed before it is locked in a set position.

It is an object of this invention, therefore, to provide an improved control device for control apparatus and particularly for tunable radio apparatus.

Another object of this invention is to provide control apparatus having a plurality of articulated selector units, each of which has pivoted finger-operated means adapted to be pivotally

manipulated for adjusting the unit to a predetermined tuning position.

A further object of this invention is to provide a selector unit for control apparatus which is simple and rugged in construction, comprised of a small number of stamped out parts, and adapted to be easily and positively locked in a predetermined tuning position by a simple one-hand manipulation of a pivoted actuating member in an up or down direction.

15 A feature of this invention is found in the provision of a selector unit of articulated construction having the parts thereof locked in fixed relative positions when a pivoted actuating portion is in longitudinal alignment with a body portion of the selector unit, and in which the adjustable element is released for adjustment when the actuating portion is pivotally moved from such longitudinally aligned position.

20 Yet another feature of this invention is the provision of control apparatus particularly adapted for tuning radio receiver apparatus which may be set to tune various predetermined frequencies by a setting operation requiring merely a substantially vertical movement of pivoted finger-operated means.

25 Further objects, features and advantages of this invention will become apparent from the following description when taken in connection with the accompanying drawing in which:

Fig. 1 is a side view of a complete assembly of the invention;

Fig. 2 is a sectional view as seen along the line 2—2 in Fig. 1;

30 Fig. 3 is illustrated similarly to Fig. 2 showing parts thereof in changed position; and

Fig. 4 is a side view of a modified form of the invention.

35 In the practice of this invention there is provided a selector unit including a carriage member having a substantially longitudinally extending flat portion. An adjustable element is adjustably supported on the body portion and adapted for engagement with rotary control means when the selector unit is in its home position. A friction unit for locking the adjustable element in an adjusted position is supported on the carriage member with a portion thereof positioned between the adjustable element and one end of an actuating member, which is pivotally supported at such one end on the carriage member body portion. The actuating member is adapted to be pivotally moved into longitudinal alignment with the carriage member body portion, with its movement to such

aligned position moving the friction unit to its position for locking the adjustable element. On pivotal movement of the actuating member out of its aligned position, the friction unit is released to permit free adjustment of the adjustable element.

The tuning device of the invention is illustrated in Fig. 1 with representative rotary control means such as a treadle bar 10 rotatably supported in fixed frame means 11 and operatively connected with suitable frequency changing means (not shown), in a manner to rotate the frequency tuning means through an angular distance of 180° to provide for a full range of tuning. The treadle bar 10 is illustrated as being of a substantially V-shaped section, having engaging portions or sides 12 and 12' supported in a spaced relation by an integral slotted portion 13. Rotation of the treadle member 10 to provide for a predetermined frequency tuning position of the frequency changing means is accomplished by means of its operative association with a usual manual control knob, (not shown) and also by actuation of station selector or push button units 14, only one of which is shown.

The push button 14 includes a carriage or operating member 16 and an actuating or finger-operated member 17 having a knob 18 thereon. The carriage member is of an irregular shape and formed with an upwardly extending projection 19 and a substantially longitudinally extending flat portion 21. The carriage member is pivotally supported for pivotal movement to two operating positions at the projection 19 on a pin or axis means 22 mounted in the side walls (not shown) of the frame means 11, the pin 22 being inserted through a corresponding aperture formed in the projection 19. As shown in Fig. 1, the carriage member, and hence the selector unit, is in its rest or idle position, which is defined by the engagement of the flat side 23 of the carriage member with a front wall 24 of the frame means 11. Movement of the selector unit to this rest position is accomplished by a spring 26 which is connected at one end to the carriage member and at its opposite end to a portion of the frame means 11.

An adjustable cam or driving element 27 of substantially semi-circular shape is rotatably supported by a pin 28 or the like near one end of the carriage body portion 21, with its flat portions 29 and 29' facing normally in the direction of the treadle bar 10 for engagement with the portions 12 and 12', respectively. Axis means 30 in alignment with the pivot 28 longitudinally of the carriage body portion 21 pivotally supports the actuating member 17 at its end 31 on the carriage portion. The end 31 of the actuating member is of substantially accurate contour and is formed with a flat portion thereon to provide a cam 32 at such end for a purpose to be later explained. A friction or spring unit 33 for locking the element 27 in an adjusted position is supported near its upper end on the carriage member on a pivot 34, with its opposite end 36 positioned intermediate the adjustable cam 27 and the end 31 of the actuating member 17. The end 36 of the spring unit 33 is substantially flat with its side adjacent the adjustable element 27 having a contour adapted for mating engagement with the circular contour of the element 27. The other side of the spring end 36 is of straight form and engageable with the cam 32 at the end 31 of the actuating member 17. It is seen, therefore, that the movement of the spring end 36

longitudinally of the carriage portion 21 is limited in one direction by a fixed stop provided by the cam element 27 and in an opposite direction by an adjustable stop provided by the cam 32 at the end 31 of the actuating member 17.

As previously mentioned the spring end 36 is of substantially flat form. In practice it is contemplated that the distance between the arcuate edge of the adjustable element 27 and the edge 10 of the cam 32 for one operating position of the actuating member be such that the spring end 36 is longitudinally freely expansible therebetween to permit a substantially free movement of the element 27 about its pivot 28. This non-holding or non-friction applying position of the spring unit is illustrated in Fig. 3 and occurs when the actuating member 17 is in the position shown by dotted lines in Fig. 1. On pivotal movement of the actuating member to its full-line position shown in Fig. 1, the high portion 20 of the cam 32 is rotated against the spring end 36, which is contracted between the cam and the element 27 in a manner to apply a frictional holding pressure on the element sufficient to positively lock it in an adjusted position.

It is to be understood, of course, that the spring end 36 need only be assembled relative to the adjustable element 27 and the cam portion 32 such that the spring in its released position 30 may expand sufficiently to reduce the frictional pressure applied on the cam element 27 and to permit a free rotation thereof. Since only a slight contraction of the spring end 36 is necessary to effect a large frictional pressure on the adjustable element 27 it is apparent, therefore, that but a very small rise in the cam portion 32 and a correspondingly small pivotal movement of the actuating member 17 is required to securely lock the element 27 in an adjusted position.

The spring unit when in its element holding position is bowed laterally outwardly from the carriage portion 21, as is clearly shown in Fig. 2, the spring pressure resulting from the spring contraction provided by the cam 32 and the extensive bearing surface between the spring and element 27, positively locking the element 27, the spring 33 and the actuating member 17 in fixed positions relative to the carriage member 16. Since the spring end 36 is of a smaller thickness than the element 27 and actuating member 17, a spacing or rest block 25 bumped out from the carriage portion 21 intermediate the element 27 and cam 32 is provided to retain the spring end 36 away from the carriage portion and in an engaging position relative to such two defined parts. Wedging of the spring end between one of such two parts and the carriage member is thus entirely eliminated so that a positive action of the spring for locking the element 27 is provided whenever the cam 32 is moved into frictional engagement therewith.

As shown in Fig. 1 the actuating member 17, when the unit 33 is in its pressure applying or holding position, is extended longitudinally of the carriage portion 21. The unit 14 is thus seen to be of articulated construction, with the actuating member being pivotally movable out of longitudinal alignment with the carriage portion 21 to release the spring 33 from its element locking position, and into longitudinal alignment therewith to move the spring into its locking position. Pivotal movement of the actuating member to its operating positions is defined by lugs or stops 37 and 37' punched out on the carriage member 16. When the actuating member,

therefore, is in an operating position extended longitudinally of the carriage portion 21 the selector unit 14 is set to rotate the treadle bar 10 to a predetermined control position as will now be described.

In the operation of the selector unit 14 let it be assumed that the treadle bar 10 is manually rotated to a control position corresponding to a predetermined tuning position of the frequency changing means to which the selector unit is to be set. With the selector unit in its rest position, as shown in Fig. 1, the knob 18 on the actuating member is manually gripped and pulled upwardly to pivotally move the actuating member from its position against the lug 37' to its dotted line position against the lug 37. By virtue of the pivotal support of the selector unit on the pivot 22 and the engagement of the carriage member side portion 23 against the frame wall 24, the rest position of the selector unit 14 is positively retained during this pivotal movement of the actuating member 17, so that the release of the spring unit 33 from a holding to a non-holding position relative to the adjustable element 27 is simply accomplished by a one-hand manipulation of the actuating member.

With the actuating member in its dotted line position the selector unit 14 is pivotally moved inwardly toward the treadle bar 10, the portions 29 and 29' on the adjustable element 27 moving into engagement with the corresponding portions 12 and 12' on the treadle bar 10, because of the element 27 being freely rotatable on the pivot 28. While the element 27 is engaged with the treadle bar 10 the actuating member 17 is pivotally moved downwardly from its dotted line position to its full-line position against the lug 37' whereby to move the spring 33 to its friction applying position for locking the element 27 in such adjusted position in the manner above fully described. Because of the pivotal support of the selector unit 14 at the pivot 22 and the engagement of the cam 27 against the treadle bar 10, the unit 14 is retained stationary in its home position while the actuating member 17 is pivotally manipulated. It is seen, therefore, that both the release and the locking of the element 27 is simply accomplished merely by pivotally moving with one hand the actuating or finger operated member 17.

On locking of the element 27 in its adjusted position the actuating member 17 is released and the selector unit 14 is returned to its rest position by the action of the spring 26. With all of the parts of the selector unit locked in fixed relative positions, it is apparent of course that later actuation of the selector unit to its home position operates to rotate the treadle bar 10 to the control position for which the selector unit has been set. It is contemplated that the axis of the treadle bar 10 be positioned in the arcuate path taken by the element axis means 28 on pivotal movement of the selector unit 14 to provide for an increased accuracy in the element setting.

In the modified form of the invention shown in Fig. 4, the carriage unit 16' is provided with a flat body portion 38 having the adjustable element 27 at one end thereof, the opposite end of the body portion being slidably supported in a front panel portion 24' of frame means 11'. Extending longitudinally from the body portion 38 is an extension 39 which is slidably supported on and extended through a frame element 41. Mounted about the projection 39 and between the

frame element 41 and the body portion 38, is a spring 42 adapted to retain the selector unit 14' in its idle or rest position, this position being defined by the engagement of a shoulder portion 43 on the carriage member with the front wall 24' of the frame means 11. The element 27, a spring unit 33', and an actuating member 17' are substantially similar in all respects to the corresponding parts in Fig. 1, so that a further description of the construction of and relative assembly of these parts is believed to be unnecessary.

In the adjustment of the selector unit 14' to a setting corresponding to a predetermined control position of the treadle bar 10, the actuating member 17' is pivotally moved upwardly from its full-line position to its dotted-line position, as shown in Fig. 4, to release the spring unit 33' from its element locking position. With the actuating member 17' in its dotted-line position, the selector unit 14' is linearly moved into engagement with the treadle bar 10 to rotate the adjustable cam element 27 to a position corresponding to the predetermined control position of the treadle bar. It is to be understood, of course, that the element 27 is freely rotatable about its pivot 28 by virtue of the release of the spring unit 33' from its friction applying position on movement of the actuating member to its dotted line position against the stop 37. After the element 27 has been thus rotated to its adjusted position the actuating member 17' is moved pivotally downward against the stop 37' to lock the element in such adjusted position. On release of the actuating member 17' the unit 14' is returned to its rest position by the action of the spring 42. Because of the slidable support of the carriage member 16' in the front wall 24' and in the frame element 41, the selector unit 14' is positively retained in each of its home and rest positions during the manipulation of the actuating member 17', so that setting of the selector unit 14' is simply accomplished by a one-hand manipulation of the actuating member 17'. The lug 37' defines a position of the actuating member 17' in longitudinal alignment with the body portion 38 so that the selector unit 14' is in substantial alignment longitudinally when it is actuated in normal operation by pushing inwardly on the finger knob 18'.

From the above description and consideration of the drawing, it is seen that the invention provides control apparatus which can be readily adjusted to various predetermined positions for accomplishing tuning at those positions. In both of the illustrated embodiments the adjustable element is releasably locked in a set position by friction means including a member having a portion thereof in a plane substantially parallel to the plane of the carriage member and parallel or coplanar with the plane of the adjustable element. The frictional forces are applied and removed simply and with one hand by merely pivotally moving in an up-and-down direction a finger operated member. Particularly in the case of small or portable receiving sets, it is apparent that this direction of movement of the finger-operated member and the adjustment of the selector unit, practically eliminates any movement of the receiving set during the adjusting operation because of the application of the locking and releasing forces in a substantially vertical direction.

Although the invention has been specifically described with reference to two embodiments thereof, it is to be understood that it is not to

be so limited, since modifications and alterations in the parts and their arrangement can be made therein which are within the intended scope of this invention as defined by the appended claims.

I claim:

1. In control apparatus having rotary control means, the means for rotating said rotary control means to predetermined control positions including a movable carriage unit having an adjustable element pivotally supported thereon, an actuator unit pivotally supported at one end on said carriage unit, with said one end having a cam portion thereon, friction means for locking said adjustable element in an adjusted position, and means supporting said friction means on said carriage unit intermediate said adjustable element and said cam portion, said cam portion on pivotal movement of said actuator unit in one direction moving said friction means to apply a frictional pressure on said adjustable element to lock the same in an adjusted position.

2. In control apparatus having movable control means, the means for moving said movable control means including an articulated selector unit having a movably supported body portion and a finger-operated portion, means pivotally supporting said finger operated portion at one end on said body portion, an adjustable element adjustably supported on said body portion, friction means for locking said adjustable element in an adjusted position, means supporting said friction means on said body portion intermediate said adjustable element and finger-operated portion, said adjustable element defining the movement of said friction means in one direction, and the one end of said finger operated portion defining movement of said friction means in an opposite direction, said one end having a cam surface thereon operatively engageable with said friction means, with pivotal movement of said finger-operated portion in one direction engaging said cam surface and friction means to move said friction means to a position for applying a frictional locking pressure on said adjustable element.

3. In control apparatus having movable control means, the means for moving said control means to predetermined control positions including a carriage unit, means movably supporting said carriage unit for movement to two operating positions, finger-operated means pivotally supported at one end on said carriage unit, said one end having a cam portion thereon, an adjustable element adjustably supported on said carriage unit, and a flat spring member supported on said carriage unit intermediate said adjustable element and the one end of said finger-operated means, with one portion of said flat spring being frictionally engageable with said adjustable element and an opposite portion thereof being engageable with said cam portion, said cam portion on pivotal movement of said finger-operated means in one direction, when said carriage unit is in one of said operating positions, urging said flat spring into frictional engagement with said adjustable element to lock the same in an adjusted position.

4. In control apparatus having movable control means, an articulated selector unit for moving said control means having a body portion and a finger operated portion, means pivotally supporting said finger-operated portion at one end on said body portion, said one end having a cam surface thereon, an adjustable element adjustably supported on said body portion and

operatively engageable with said movable control means, means movably supporting said body portion for movement to two operating positions, means for applying a frictional pressure on said

5 adjustable element to lock the same in an adjusted position, and means supporting said locking means on said body portion intermediate said adjustable element and the end of said finger-operated portion, said cam surface on pivotal movement of said finger-operated portion when said body portion is in one of said operating positions engaging said locking means to apply a frictional locking pressure on said adjustable element, said finger-operated means being pivotally movable in an opposite direction when the body portion is in the other of said operating positions to provide for the release of said locking pressure on said adjustable element.

6. In control apparatus having movable control means, the means for moving said control means including a supporting unit and an actuating member, means pivotally connecting said actuating member at one end with said supporting unit for movement to two operating positions, said one end having a cam portion thereon, an adjustable element adjustably supported on said supporting unit, a substantially flat spring unit for applying a frictional holding pressure on said adjustable element to lock the same in an adjusted position, means supporting said spring unit on said supporting unit in a plane substantially parallel to the plane of said supporting unit and in a position intermediate said adjustable element and said cam portion, said spring unit when said actuating member is in one of said operating positions being in a non-holding position relative to said adjustable element, with pivotal movement of said actuating member to the other of its operating positions engaging said cam portion and said spring unit to urge the same into a frictional holding position relative to said adjustable element.

7. In control apparatus having movable control means, the means for moving said control means including a carriage unit and finger operated means, means movably supporting said carriage unit for movement to two operating positions, with a longitudinal portion of said carriage unit being movable in a substantially linear direction, means pivotally supporting said finger operated means at one end on said carriage unit, with said one end having a cam portion thereon, an adjustable element adjustably supported on said longitudinal portion, means for applying a frictional holding force on said adjustable element to lock the same in an adjusted position, means supporting said locking means on said carriage unit intermediate said adjustable element and cam portion, said locking means being urged into a friction applying position by said cam portion when said finger operated means is in substantial longitudinal alignment with said carriage portion, and said adjustable element being adjustable when said finger operated means and carriage portion are out of longitudinal alignment, said carriage unit when said adjustable element is in an adjustable position being movable to one of said operating positions by said finger operated means, with said element being locked in an adjusted position at said one operating position on pivotal movement of the finger operated means into longitudinal alignment with said carriage portion, said finger operated means when said carriage unit is in the other of said operating positions being piv-

totally movable to release the holding pressure on said adjustable element, and means retaining said carriage unit stationary in said operating positions on manipulation of said finger operated means to frictionally lock and release said adjustable element.

7. In control apparatus having movable control means, the means for moving said control means including a carriage unit and finger-operated means, means supporting said carriage unit for movement to two operating positions, said carriage unit having a substantially linearly movable longitudinal portion, axis means pivotally supporting said finger-operated means at one end on said carriage unit, said one end having a cam portion thereon, an adjustable element, second axis means pivotally supporting said adjustable element on the longitudinal portion of said carriage unit, said two axis means being in substantial alignment longitudinally of said carriage unit portion, friction means adapted to apply a frictional holding pressure on said adjustable element to lock the same in an adjusted position, means supporting said friction means on said carriage unit in a position intermediate said adjustable element and cam portion, said finger-operated means being in longitudinal alignment with said carriage unit portion to normally engage said cam portion and friction means for applying a frictional holding pressure on said adjustable element, said finger-operated means when said carriage unit is in one of said operating positions being pullable upwardly out of longitudinal alignment with said carriage unit portion to release said friction means from a friction-applying position, said carriage unit with said finger-operated means in said upward position being movable to the other of said operating positions, with said finger-operated means being pushable downwardly when said carriage is in said other operating position to move said friction means into friction applying position, and means supporting said carriage unit on at least two points when it is in each of said operating positions to retain the carriage unit stationary during the manipulation of said finger-operated means.

8. In control apparatus having movable control means, the means for moving said control means to predetermined control positions including a carriage member having a substantially flat longitudinally extending body portion, an adjustable element adjustably supported on said body portion, an actuating member pivotally connected at one end to said carriage member, said one end having a cam portion thereon, a substantially flat spring unit supported on said body portion and adapted to frictionally hold said adjustable element in an adjusted position, with a portion of said spring unit being positioned intermediate said adjustable element and said cam portion, said adjustable element, spring portion, and cam portion lying in a plane substantially parallel to the plane of said carriage member body portion, and means on said body portion supporting said spring portion laterally therefrom, said cam portion on pivotal movement of said actuating member to a position in longitudinal alignment with said carriage member body portion engaging and bowing said spring unit to apply a frictional holding pressure on said adjustable element.

9. In control apparatus having movable control means, the means for moving said control means to predetermined control positions includ-

ing a carriage unit having a substantially flat longitudinally extending body portion, finger-operated means pivotally supported at one end on said body portion for pivotal movement to a position in longitudinal alignment therewith, said one end having a cam portion thereon, an adjustable element adjustably supported on said body portion, a substantially flat spring unit for applying a frictional holding pressure on said adjustable element to lock the same in an adjusted position, means supporting said spring at one end on said body portion, with its opposite end positioned substantially intermediate said adjustable element and cam portion, said spring unit being in a plane substantially parallel to the plane of said body portion when in a non-friction applying position, and said cam portion on pivotal movement of said finger-operated means to said longitudinally aligned position engaging and moving said opposite spring end into frictional engagement with said adjustable element, with said spring unit in its element holding position being laterally bowed relative to the plane of said body portion.

10. In control apparatus having movable control means, the means for moving said control means to predetermined control positions including a supporting member having a flat body portion, an adjustable element, axis means rotatably supporting said adjustable element on said body portion, finger-operated means, second axis means pivotally supporting said finger-operated means at one end on said body portion, said two axis means being in alignment longitudinally of said body portion, a spring unit adapted to apply a frictional holding pressure on said adjustable element to lock the same in an adjusted position, and means supporting said spring unit at one end on said carriage unit, with its opposite end positioned intermediate said two axis means, with movement of said opposite spring end being confined longitudinally of said body portion by said adjustable element and the one end of said finger-operated means, said one end having a contour such that on pivotal movement of said finger-operated means in one direction said spring unit is urged thereby into frictional engagement with said adjustable element, with said finger-operated means on pivotal movement thereof in an opposite direction releasing said spring unit to permit adjustment of said adjustable element.

11. In control apparatus having movable control means, the means for moving said control means including an operating unit and an actuating unit, means pivotally supporting said operating unit for pivotal movement to two operating positions, said operating unit having a flat longitudinally extending portion movable in a substantially linear direction between said two operating positions, an adjustable element adjustably supported on said flat portion, means pivotally supporting said actuating unit at one end on said flat portion, said one end having a cam portion thereon, a friction element for applying a frictional holding force on said adjustable element to lock the same in an adjusted position, means supporting said friction unit on said operating unit intermediate said adjustable element and said cam portion, said friction element having one side engageable with said adjustable element and an opposite side engageable with said cam portion, said actuating unit on pivotal movement thereof in one direction transversely of said flat portion when said operating

unit is in one of said operating positions moving said cam portion to permit relative movement between said adjustable element and the one side of said friction element, with pivotal movement of said actuating unit in an opposite direction into longitudinal alignment with said flat portion when said operating unit is in the other of its operating positions moving said cam portion into engagement with the opposite side of said friction element to frictionally engage the one side of said friction element with said adjustable element, means defining the two operating positions of said carriage unit, and stop means on said carriage unit for limiting the pivotal movement of said actuating unit.

12. In control apparatus having movable control means, the means for moving said control means including a carriage unit having an adjustable element adjustably supported thereon, means slidably supporting said carriage unit for longitudinal movement to two operating positions, a finger-operated unit, means pivotally supporting said finger-operated unit at one end on said carriage unit for pivotal movement transversely of said carriage unit, said one end having a cam portion thereon positioned in alignment with said adjustable element substantially longitudinally of said carriage unit, a flat spring member for frictionally locking said adjustable element in an adjusted position, means supporting said spring member on said carriage unit intermediate said adjustable element and said cam portion for cooperative engagement therewith, said cam portion on pivotal movement of said finger-operated unit into longitudinal alignment with said carriage unit, when the carriage unit is in one of said operating positions, bending said spring member against said adjustable element to apply a frictional locking pressure on said element, with said cam portion on pivotal movement of said finger-operated unit out of said aligned position when said carriage unit is in the other of said operating positions releasing said spring member until it is of substantially straight line contour to permit relative movement between said spring member and said adjustable member, and means on said carriage unit for limiting the pivotal movement of said finger-operated unit.

13. In a control unit having a body portion with adjustable means thereon, an actuating member pivoted on said body portion, resilient locking means operatively connected with said adjustable means and actuating member, and means mounting said resilient means on said body portion, said actuating member on pivotal movement to one operating position therefor acting on said resilient means to produce a frictional pressure therein for application on said adjustable means and actuating member, said frictional pressure locking said adjustable means in an adjusted position and releasably retaining said actuating member in said one operating position.

14. In a control unit having a body portion with pivoted adjustable means thereon, a pivoted finger-operated member supported on said body portion, and resilient means operatively connected with said adjustable means supported on said body portion, said finger member having

5 an engaging portion in slidable engagement with said resilient means, said resilient means on pivotal movement of said finger member in one direction to one operating position therefor being acted upon by said engaging portion to exert a frictional pressure against said adjustable means and finger member, said frictional pressure locking said adjustable means in an adjusted position and releasably retaining said finger member in said one operating position, said engaging portion on pivotal movement of said finger member in a reversed direction releasing said resilient means to permit a free pivotal movement of said adjustable means.

15. 15. In a control unit having a body portion and pivoted adjustable means thereon, a pivoted finger-operated portion supported on said body portion and pivotally movable to a rest and an operating position, means for locking said adjustable means in an adjusted position concurrently with the pivotal movement of said finger portion from said rest to said operating position including resilient means supported on said body portion operatively connected with said adjustable means and finger portion, said finger portion on pivotal movement thereof to said operating position acting on said resilient means to produce a pressure therein for application on said finger portion and adjustable means, said pressure locking said adjustable means in an adjusted position and releasably retaining said finger portion in said operating position, with pivotal movement of said finger portion to said rest position releasing said pressure to provide for the free pivotal movement of said adjustable means.

16. In a control unit having a body portion with adjustable means thereon, a pivoted finger-operated portion supported on said body portion, pivotally movable to one position to release said adjustable means and to a second position to lock the adjusted means in an adjusted position, and means operatively connecting said adjustable means and finger-operated portion including resilient means supported on said body portion, said finger portion on pivotal movement thereof from said one to said second position acting on said resilient means to deform the same and produce a pressure therein for application on said finger portion and adjustable means, said pressure providing for the frictional locking of said adjustable means in an adjusted position and the frictional holding of said finger portion in said second position.

17. In a control unit having a body portion and adjustable means thereon, resilient means operatively connected with said adjustable means, means mounting said resilient means on said body portion, and a pivoted finger-operated member supported on said body portion having an engaging portion in slidable engagement with said resilient means, said resilient means on pivotal movement of said pivoted member being adapted to be deformed by said engaging portion to apply a frictional pressure against said adjustable means and finger member, said frictional pressure locking said adjustable means in an adjusted position and releasably holding said finger portion in a position to retain the resilient means deformed.

ALEXANDER W. PLENSLER.
